REINHARD HILDEBRAND, OF WEBSTER GROVES, MISSOURI, ASSIGNOR TO FULTON IRON WORKS COMPANY, OF ST. LOUIS, MISSOURI, A CORPORATION OF DELAWARE.

FUEL INJECTOR FOR INTERNAL-COMBUSTION ENGINES.

Application filed March 22, 1923. Serial No. 626,855.

This invention relates to improvements in fuel injectors particularly adapted for use in engines of the Diesel type wherein compressed air is employed to inject the fuel into the combustion chambers. In an engine of this type, the delivery of fuel is ordinarily regulated by a governor, and predetermined volumes of liquid fuel are forced into a nozzle from which they are discharged by compressed air to the combustion chamber. Prior to this invention, measured charges of liquid fuel have been discharged across the passageway in the nozzle so as to impinge against one of the side walls of the passageway, and owing to the tendency of the fuel to cling to the wall, it has not been effectively removed by the compressed air. As a consequence, the engine does not quickly respond to the action of the governor, and it is liable to receive too much, or not enough, of the fuel.

It is to be understood that the fuel is injected during a very short period of time, and it is most desirable to discharge all of the fuel in the nozzle at each operation, so as to cause the predetermined charge to enter the combustion chamber. Obviously, this cannot be accomplished if a large percentage of the liquid fuel is clinging to one of the side walls of the passageway in the nozzle. In this event, some of the fuel will spread on the surface of the wall, instead of being instantly discharged to the combustion chamber.

One of the objects of the present invention is to produce a fuel injector from which each charge of fuel can be effectively discharged by compressed air, without leaving an uncertain amount of the charge clinging to the interior of the nozzle. In the preferred form of the invention, this is accomplished in a nozzle having a suitable passageway through which the compressed air is transmitted, and a fuel duct for the delivery of liquid fuel to said passageway, the discharge end of the fuel duct being directed toward the discharge end of the nozzle, so that the fuel will be readily ejected. This duct may be provided with branches, or the like, at its discharge end, so as to distribute the fuel in the interior of the nozzle, and these branches may terminate near an ordinary atomizing device onto which the liquid fuel is discharged and distributed, to effec-

tively receive the pressure of the compressed air.

With the foregoing and other objects in view, the invention comprises the novel construction, combination and arrangement of parts hereinafter more specifically described and illustrated in the accompanying drawing; wherein is shown the preferred embodiment of the invention. However, it is to be understood that the invention comprehends changes, variations and modifications which come within the scope of the claims hereunto appended.

Fig. I is a vertical section of a nozzle embodying the features of this invention, showing portions of the cylinder head to which the nozzle is secured.

Fig. II is a side elevation of the tube having channels for the distribution of the liquid fuel.

Fig. III is a section on the line III—III in Fig. I.

The cylinder head comprises upper and lower walls 1 and 2 separated from each other to provide a space for the cooling medium. The nozzle comprises a tubular housing 3 provided at its lower end with a valve seat 4 and a discharge tip 5 secured to the member 4 by means of a threaded ring 6, the latter being screwed onto member 4 and provided with an inturned flange 85 engaging a flange on the member 4. A sleeve 7, surrounding the tubular member 3, is seated in the lower wall 2 of the cylinder head, the upper end of this sleeve being extended into an opening 8 in the upper wall 1 and engaged by a threaded ring 9 screwed into said opening. The sleeve 7, mounted in this manner, is intended to prevent leakage of water at the openings in which the nozzle is secured.

A needle valve 10, extending from the upper end of the nozzle, is provided at its lower end with a tapered face 11 adapted to engage a correspondingly tapered face in the valve seat member 4. 12 designates a tubular guide in which the valve is mounted, and 13 is a stuffing box at the upper end of said guide. A flange 14, extending from the lower portion of the stuffing box, lies between a clamping member 15 and the upper end of the tubular housing 3, said upper end being enlarged to receive studs 16 which are screwed into the cylinder head and ex-

tended upwardly through the clamping member 15 to receive nuts 17. The downward pressure of nuts 17 is transmitted through clamping member 15 and flange 14 to the tubular member 3, so as to force the valve seat member 4 onto a gasket 18 in the wall 2.

A tube 19 is surrounded by and closely fitted to the inner face of the tubular housing 3, and this tube has a tapered lower end engaging a correspondingly tapered portion of the housing. 20 designates a threaded ring screwed into the upper end of housing 3 and engaging the upper end of tube 19 so as to firmly force its tapered lower end onto the corresponding seat in the housing 3. A series of openings 21, formed in the upper end of tube 19, are in free communication with a passageway 22 providing an inlet for compressed air. The air flowing from passageway 22 flows through the openings 21 to the interior of tube 19, and thence downwardly to the discharge end of the nozzle, as will be hereafter described.

25 23 designates a passageway formed in the enlarged upper end of housing 3 to provide for the admission of liquid fuel. This passageway terminates at the inner face of tubular member 3. The fuel-distributing 30 passageways are formed partly by the inner face of tubular member 3 and partly by channels in the outer face of tube 19, the latter being closely fitted to said inner face.

Channels 24 (Figs. I and II) diverge from 35 the fuel inlet 23 to the tapered lower portion of tube 19, and these channels have diverging branches 24' extending to the lower edge of said tapered portion. The lower ends of the main channels 24 are at diametrically 40 opposite points in the tube 19, and the branches 24' terminate at four equidistant points in the lower end of the tube, as shown most clearly by Fig. III. The stream of liquid fuel is thus divided and distributed 45 through ducts having their discharge ends directed toward the discharge end of the nozzle. The streams of fuel issuing from the ducts, or channels 24', are discharged in a direction conforming approximately to the 50 direction of the compressed air flowing through the nozzle, and the liquid fuel will be effectively discharged with the air.

A series of atomizing plates, or rings 25, rest upon a cone 26 seated in the tapered 55 opening in member 4, said cone having peripheral slots 27 through which the mixture of air and liquid fuel is conducted, and the plates 25 are provided with small perforations forming passageways for the fuel and 60 air. This atomizing device surrounds the lower end of the tubular guide 12 and lies

between the lower end of tube 19 and the discharge end of the nozzle.

Instead of being discharged onto the side walls of the main passageway in the nozzle, 65 the small streams of fuel issuing from ducts 24' are preferably discharged directly onto the top face of the atomizing elements 25, and the liquid fuel is distributed on this top face where it can be effectively acted upon 70 by the compressed air and readily discharged from the nozzle.

I claim:

1. In a fuel injector for internal combustion engines, a tubular housing having a fuel inlet, an air inlet and an outlet for the discharge of air and liquid fuel, a tube surrounded by and closely fitted to the inner face of said housing, said tube having a tapered end engaging a correspondingly tapered portion of said housing, a valve extending through said tube and seated in said outlet to control the discharge therefrom, said air inlet being in communication with said tube to provide for the delivery of compressed air therethrough, the outer face of said tube having a channel communicating with said fuel inlet and provided with discharge branches in said tapered end, and said discharge branches being directed toward said outlet to provide for the discharge of streams of liquid fuel in approximately the direction of flow of the compressed air.

2. In a fuel injector for internal combustion engines, a tubular housing having a fuel inlet, an air inlet and an outlet for the discharge of air and liquid fuel, a tube surrounded by and closely fitted to the inner face of said housing, said tube having a tapered end engaging a correspondingly tapered portion of said housing, a valve extending through said tube and seated in said outlet to control the discharge therefrom, said air inlet being in communication with said tube to provide for the delivery of compressed air therethrough, a fuel-atomizing device between said outlet and the tapered end of said tube, the outer face of said tube being provided with channels diverging from said fuel inlet and having diverging discharge branches in said tapered end to provide for distribution of the liquid fuel, and said discharge branches being directed toward said fuel-atomizing device so as to discharge the fuel in a direction conforming approximately to the direction of the compressed air.

In testimony that I claim the foregoing I hereunto affix my signature.

REINHARD HILDEBRAND.
